CASTER FOR CONDIMENT DISPENSERS
OR THE LIKE

Norman E. Roe, Sierra Madre, Calif., assignor to Dispensers, Inc., Goleta, Calif., a corporation of California

Filed Oct. 1, 1962, Ser. No. 71,935

Term of patent 14 years

(Cl. D44—7)

FIG. 1 is a perspective view of a caster for condiment dispensers or the like showing my new design;

FIG. 2 is a side elevational view thereof;

FIG. 3 is a sectional view of the upright portion taken along line 3—3 of FIG. 2; and

FIG. 4 is a bottom plan view thereof.

I claim:

The ornamental design for a caster for condiment dispensers or the like, substantially as shown.
